ALBERT H. STEBBINS, OF LOS ANGELES, CALIFORNIA.

CONCENTRATOR TABLE.

Application filed January 8, 1927. Serial No. 159,817.

This invention relates to improvements in concentrator decks and more particularly to the arrangement of the riffles.

Concentrator decks as constructed heretofore to treat ores or other comminuted materials in the dry state usually have a deck surface that is supported at a transverse inclination, and riffles which extend diagonally over the deck surface serve to direct the concentrates toward the upper side of the deck while the tailings flow laterally over the riffles toward the lower side of the deck, and travel of the materials lengthwise of the deck is effected by imparting to the deck a progressive vibratory movement.

While the type of deck just described works very well, it is found that separation of the larger concentrates from the tailings may be expedited by arranging the riffles approximately lengthwise of the deck rather than diagonally thereof, but unless the diagonal riffles are employed to work the concentrates up the inclined deck surface, the concentrates are not directed away from the lower or tailing side of the deck.

Having in mind the foregoing the present invention contemplates a novel deck construction whereby riffles that extend approximately lengthwise of the deck are employed in combination with diagonally disposed riffles, with the result that the high grade concentrates are separated from the tailings more rapidly than heretofore while the diagonally disposed riffles work the concentrates away from the lower side of the deck.

One important feature of the invention resides in a deck surface having a series of riffles arranged adjacent the upper side of the deck so that they will promote the rapid travel of the concentrates along the deck, and having other riffles positioned upon the remaining portion of the deck at an angle to the first mentioned group of riffles to direct the concentrates up the inclined deck surface.

Another feature of the invention resides in a deck casing having that portion of the deck surface lying near the upper side of the deck bent upwardly at an increased angle to increase the slope of the portion of the deck upon which the longitudinally extending riffles are provided.

Still another feature of the invention resides in a deck which is constructed to form a material confining pan along the lower side of the deck to confine the materials upon

the deck surface and to subject them to a panning action under the influence of the vibratory movement imparted to the deck.

The features above mentioned when embodied in a single deck cooperate in a satisfactory manner to produce an efficient concentrator deck having a wide range of use. For example, it is found that unless the larger concentrates are rapidly separated out of the tailings they are likely to be crowded upwardly above the riffles by the finer concentrates that tend to work downwardly under the large concentrates. The riffles arranged along the upper side of the deck to advance the high grade values rapidly along the deck, effect the desired prompt separation of the larger values from the tailings and finer values, and in this manner these high grade values are prevented from working down the deck into the pan forming portion of the deck. The concentrates that work downwardly under the tailings in the panning operation are directed up the inclined deck away from the tailings by the inclined riffles.

Other features of the invention and novel combination of parts in addition to the above will be hereinafter described in connection with the accompanying drawings which illustrate good practical forms of the invention.

In the drawings—

Fig. 1 is a side elevation of a concentrator table having a deck constructed in accordance with the present invention;

Fig. 2 is a sectional view taken on the line 2—2 of Fig. 1;

Fig. 3 shows the deck of Fig. 2 on a somewhat enlarged scale;

Fig. 4 is a top plan view of the deck of Fig. 1; and

Fig. 5 is a view similar to Fig. 4 but shows a modified type of deck construction.

The concentrator table and the deck shown in the drawings for the most part may be constructed as usual and it will be noted that the deck frame 10 is shown as mounted upon the carriage 11 which is supported by the concentrator frame for movement back and forth in the direction of its length.

The concentrator frame may be provided with the uprights 12 to which the longitudinally extending side rails 13 are secured, and the opposite sides of the frame are connected by the transversely extending brace 14. The carriage 11 may be supported from

the concentrator frame for vibratory movement in the direction of its length by the anti-friction balls or rollers 15 which are confined between bearing blocks 16 secured to the supporting frame, and similar bearing blocks 17 secured to the under face of the carriage 11.

Various means may be employed for imparting a vibratory movement to the deck 10 and carriage 11 to advance the materials lengthwise of the deck, and the means shown to this end consists of the spaced operating cables 18 each of which has an intermediate portion secured to the under face of the carriage 11 by the clamping blocks 19, and the right-hand end portion of each cable is shown in Fig. 1 as extending downwardly around a grooved sheave 20 which is rotatably supported by a transversely extending shaft 21 mounted upon the concentrator frame. The portion of each cable 19 which extends downwardly from the grooved sheave 20 is secured to a coiled spring 22. The portion of each cable 18 which extends in a left-hand direction from the clamp 19 is looped about a similar grooved sheave 20 supported by a transversely extending shaft 23 and a portion of each cable extends from the lower face of the sheave last mentioned about a third grooved sheave 24 which is rotatably mounted upon an eccentric 25, and that portion of each cable which extends from the lower face of the grooved sheave 24 is anchored to the supporting frame as at 26. Each eccentric 25 is rigidly secured to the power shaft 27 having the driving pulley 27^a. The arrangement just described is such that the deck 10 is normally urged in a right-hand direction by the pull exerted upon the cables 18 by the compressed springs 22 and rotation of the power shaft 27 will rotate the eccentrics 25 within the grooved sheaves 24 to move these sheaves bodily in an orbital path to thereby tension and slack off the portion of each cable 18 engaging a sheave 24. This will serve to pull the deck 10 in a left-hand direction and then release it to move in the right hand direction under the action of the springs 22. By varying the strength of the springs 22 a progressive movement of any desired intensity may be imparted to the deck, to advance the materials lengthwise of the same.

The construction so far described forms no essential part of the present invention and may be varied as desired.

The deck casing 10 is shown as mounted upon the carriage 11 so that it extends at a transverse inclination and the lower side of the deck is secured to the carriage 11 by the hinges 28, while the upper side of the deck is supported in spaced relation to the carriage by the posts 29 having the adjustable nuts shown. The deck frame 10 is provided with the material supporting sur-

face 30 to which the materials to be treated may be delivered by the feed hopper 31 disposed adjacent the left-hand end of the deck, and the rate at which the materials are delivered to the deck may be controlled by 70 adjusting the feed gate 32. Below the material supporting surface 30 is provided the usual air chamber 33 to which air may be delivered under pressure by the blast fan 34 the discharge end of which is connected by a 75 flexible connection 35 to the hood 36 leading into the air chamber 33.

The general configuration of the deck may be varied as found desirable but preferably has substantially the configuration shown in 80 Figs. 4 and 5 wherein it will be seen that the deck is relatively wide at its material receiving end and gradually decreases in width towards its right-hand or concentrates discharge end. At the upper side of the 85 deck is provided the usual concentrate wall 37 having the buffer blocks 38, and at the left-hand end of the deck is provided the usual inclined wall 39 which extends downward from the feed hopper to the lower side 90 of the deck.

As above pointed out it is desirable to so construct the riffles that the larger or high grade concentrates will be quickly separated from the tailings and advanced lengthwise 95 of the deck, and this is accomplished, in accordance with the present invention, by providing a series of riffles 40 arranged adjacent the concentrate wall 37 to extend approximately longitudinally of the deck, the 100 arrangement of the riffles being such that the concentrates will travel rapidly along the same under the influence of the deck movement. In the particular construction shown the high grading riffles 40 are arranged so that they slope downwardly 105 slightly in the direction in which the materials travel and extend downwardly across the path of deck movement, as will be apparent by observing the disposition of the 110 riffles 40 with respect to the broken line *a* which indicates the direction of deck movement. This arrangement of the riffles 40, while not essential in all embodiments of the 115 invention, is desirable because when the riffles are arranged so that they extend across the path of deck movement the movement imparted to the deck will work the concentrates across the channel formed between a pair of riffles 40 and against the 120 riffle at the upper side of the channel so that the concentrates will not escape laterally over the riffle at the lower side of this channel. The movement of the concentrates across a channel away from the lower side 125 thereof in the manner just explained displaces the tailings within the channel and crowds them out of the channel over the riffle at the lower side of the channel.

While the riffles 40 having the arrange- 130

ment herein described work effectively to separate the high grade values from the tailings, the downward inclination imparted to these riffles serves to work the materials down the deck towards the lower or tailing side thereof. This is desirable only to a small degree, and it is therefore important to provide means for working the concentrates that approach the lower side of the deck up 10 the inclined deck surface towards the concentrate wall. This is accomplished in accordance with the present invention by providing the deck surface 30 with a second set of riffles 41 which extend diagonally over 15 the deck surface as shown so that they direct the concentrates traveling along the riffles upwardly from the lower side of the deck towards the concentrate wall. The diagonally disposed riffles 41 are shown in Fig. 20 4 as arranged over a greater portion of the deck surface than in the modified construction of Fig. 5 and it will be noted that in Fig. 4 the riffles 41 are disposed adjacent the feed hopper 31, whereas in Fig. 5 the longitudinally extending riffles 40 are disposed directly below the feed hopper. The number of the longitudinally extending riffles 40 it is desirable to provide adjacent the concentrate wall 37 will depend largely 25 upon the rapidity with which it is desired to advance the high grade concentrates lengthwise of the deck, having in mind that a sufficient number of diagonally disposed riffles 41 should be employed to work the 30 concentrates away from the lower side of the deck.

The finer concentrates which are not caught by the relatively few longitudinally extending riffles 40 will work down the 40 transversely inclined deck surface towards the lower side thereof, but in doing so most of the finer concentrates will be caught by the diagonally disposed riffles 41 and will be directed up the deck surface by these inclined riffles towards the concentrate wall until they reach the longitudinally extending riffles 40 to travel lengthwise of the last mentioned riffles until they escape from the discharge end of the deck into the receptacle 42.

50 While the two sets of riffles so far described work very effectively in separating the values from the tailings, it is found that a further separation of the fine values from the tailings may be readily effected by providing an upstanding wall 43 along the lower side of the deck to form a settling basin upon the deck surface in which the tailings are retained while they are subjected to a panning action due to the vibratory movement imparted to the deck. In accordance with the present invention the tailings are caused to pile up against the retaining wall 43 in a relatively thick bed, as indicated by X in Figs. 2 and 3, so that 55 60 65 the concentrates remaining in these tailings

may work downwardly into engagement with the deck surface whereupon they will be directed out from under the bed of materials by the upwardly inclined riffles 41. The material retaining wall 43 preferably 70 extends a substantial distance along the lower side of the deck, as will be apparent from Fig. 1, in order to give the values within the bed of tailings X ample time to work downwardly into engagement with the 75 deck surface. The materials X resting against the retaining wall 43 may escape from the lower side of the deck upon reaching the inclined discharge end 44 of the retaining wall. 80

From the foregoing description when read in connection with the drawings it will be seen that the longitudinally extending riffles 40 serve to separate the large or high grade values rapidly from the tailings, thus avoiding the danger of these large values being crowded out of the riffles further down the deck by the fine values wedging under the larger values. It will be seen that by using both the longitudinally extending riffles 40 90 and the diagonally disposed riffles 41 such concentrates as work down the deck near the lower side thereof will be directed up the inclined deck surface towards the concentrate wall by the inclined riffles 41. It will 95 also be seen that by providing the basin construction above described the very fine values which might otherwise be discharged from the deck with the tailings are saved by subjecting the materials to a panning action 100 which causes these fine values to work down under the tailings into engagement with the inclined riffles. The deck surface 30 may have the usual apertures 30^a shown in Fig. 1 through which air is forced upwardly from 105 the air chamber 33.

It is found that the longitudinally extending riffles 40 will work satisfactorily upon a deck surface having a relatively steep transverse inclination, whereas the pitch or inclination of that portion of the deck provided with the riffles 41 is limited by the condition that the concentrates will not travel along the diagonally disposed riffles if the slope of the deck surface is too great. The present 115 deck surface is therefore shown as having that portion of the deck surface upon which the riffles 40 are provided bent upwardly at an increased angle as at 45.

The various features above described co-operate in a very satisfactory manner to produce a deck having a large range of utility and which separates the concentrates from the tailings with a high degree of efficiency.

What is claimed is:—

1. A concentrator table, comprising in combination, a deck casing having a material supporting surface that is mounted at a transverse inclination and having a concentrate wall that extends along the upper side 130

of the deck, means for supporting the deck for vibratory movement, riffles provided upon the deck surface near the concentrate wall and arranged to extend lengthwise of the deck at a slight angle to said wall to direct the concentrates against the concentrate wall for retreatment, and other riffles provided upon the lower portion of the deck surface and arranged at an angle to the first mentioned riffles to direct concentrates up the inclined deck toward the first mentioned riffles.

2. A concentrator table, comprising in combination, a deck casing having a material supporting surface that is mounted at a transverse inclination and having a concentrate wall extending along the upper side of the deck, riffles provided upon the deck surface near the concentrate wall and arranged to extend in the general direction of the concentrate wall and to direct the concentrates against said wall for retreatment, and other riffles provided upon the lower portion of the deck surface and arranged at an angle to the first mentioned riffles to direct concentrates up the inclined deck toward the first mentioned riffles and between different pairs of said riffles.

3. A concentrator table, comprising in combination, a deck casing having a material supporting surface that is mounted at a transverse inclination and having a concentrate wall extending along the upper side of the deck, riffles provided upon the deck surface to extend diagonally over said surface and arranged to direct the concentrates up the inclined deck surface toward the concentrate wall, and a series of riffles interposed between said wall and the upper end of the diagonally disposed riffles and arranged to extend lengthwise of the deck at an angle to the diagonally disposed riffles and constructed to receive concentrates from the first mentioned riffles and direct them against the concentrate wall for retreatment.

4. A concentrator table, comprising in combination, a deck casing having a material supporting surface that is mounted at a transverse inclination and having a portion of the deck surface extending along the upper side of the deck bent upwardly to give the same a greater transverse inclination than the remaining portion of the deck surface, riffles mounted upon said upwardly bent portion of the deck surface, and other riffles mounted upon the remaining portion of the deck surface at an inclination to the length of the deck and to said first mentioned riffles and adapted to direct concentrates up the inclined deck toward the first mentioned riffles.

5. A concentrator table, comprising in combination, a deck casing having a material supporting surface that is mounted at a transverse inclination and having a con-

centrate wall that extends along the upper side of the deck, a frame for supporting the deck casing for vibratory movement, means for vibrating the deck in the direction of its length, riffles provided upon that portion of the deck surface lying near the concentrate wall and arranged to direct the concentrates against said wall and also to slope downwardly across the path of deck movement in a direction to cause the movement of the deck to work the concentrates across the channels between the riffles toward the upper side of the channels, and other riffles provided upon the lower portion of the deck surface and extending diagonally over the deck surface to direct the concentrates up the deck surface toward said first mentioned riffles.

6. A concentrator table, comprising in combination, a deck casing having a material supporting surface that is mounted at a transverse inclination and having a concentrate wall extending along the upper side of the deck, inclined riffles provided upon the deck surface and arranged to direct the concentrates diagonally up the inclined deck surface away from the lower side of the deck, and other riffles provided upon the deck surface to direct the concentrates against different portions of the concentrate wall and arranged to extend lengthwise of the deck but with a slight downward slope toward the lower side of the deck.

7. A concentrator table, comprising in combination, a deck casing having a material supporting surface that is mounted at a transverse inclination and having a concentrate wall extending along the upper side of the deck, means for supporting the deck casing and for vibrating it to advance the materials along the deck, a material retaining wall extending along the lower side of the deck and arranged to form upon the lower portion of the deck surface a settling basin in which the materials confined therein are subjected to a panning action as the deck is vibrated, riffles provided upon the upper portion of the deck surface to extend lengthwise of the deck and adapted to direct the concentrates lengthwise of the deck and against the concentrate wall for retreatment, and other riffles arranged diagonally over the deck surface and adapted to direct the concentrates that settle in said basin out from under the tailings and up the inclined deck.

8. A concentrator table, comprising in combination, a deck casing that is supported for vibratory movement, means for vibrating the deck to advance materials along the same, a deck surface that is supported by the deck casing at a transverse inclination and having a concentrate wall extending along its upper side edge, a material

retaining wall extending along the lower side of the deck and arranged to form a settling basin upon the deck surface in which a relatively deep bed of the materials is confined to subject the materials to a panning action as the deck is vibrated, riffles provided upon the upper portion of the deck surface and arranged to direct the larger concentrates rapidly along the deck and against the concentrate wall, and other riffles extending diagonally of the deck surface and arranged to direct the concentrates that settled in said basin out from under the tailings and up the inclined deck.

15 9. A concentrator table, comprising in combination, a deck casing having a material supporting surface that is mounted at

a transverse inclination and having a concentrate wall extending along the upper side of the deck, riffles provided upon the 20 deck surface near the concentrate wall and arranged at a slight angle to said wall so that they terminate at successive points along the wall, and other riffles provided upon the lower portion of the deck surface 25 and arranged at an angle to the first mentioned riffles so that they terminate at different points along said riffles and serve to direct concentrates up the inclined deck toward the first mentioned riffles. 30

In testimony whereof, I have signed my name to this specification.

ALBERT H. STEBBINS.
